UNITED STATES PATENT OFFICE

WENDELL C. KEENER, OF PRINCETON, ILLINOIS

AERIAL SIGN

Application filed February 27, 1933. Serial No. 658,697.

This invention has reference to aerial signs. The invention has for its principal object to provide an aerial sign of self buoyant type.

The invention has for a further object to provide a sign of the character referred to wherein there is included one or a plurality of buoyant containers having the outline of or defining letters, characters, symbols or the like, each of which has associated and suitably supported in connection therewith, and as a facing therefor, a light and comparatively rigid structural shape defining a like letter, character or symbol as that defined by such buoyant container or containers.

15 A further object of the invention is to provide for the illumination of the outlines of said sign, during periods of darkness, by providing one or more of the same with an illuminating means corresponding to each of 20 the said letters, characters or symbols, and preferably recessing said illuminating means within said structural shapes.

It is a further object of the invention to provide the illuminating means in color, if 25 desired, or illuminate with a white light and provide the structural shapes with colored reflecting surfaces, and when using a colored illuminating means, said structural shapes may be provided with reflecting surfaces in 30 color or not, as may be desired.

It is a further object of the invention to provide a light and rigid frame work for the assembly of the elements of the sign into a unitary structure.

35 The invention has for a still further object the provision of supplemental buoyant means to that of the buoyant letters, characters, or symbols forming said sign.

Additional objects of the invention, attained through the provision and use of a preferred construction, embodying the fundamental principles of the invention previously set forth, are the special positioning of the device in its aerial location, whereby 45 the face thereof is angularly disposed with reference to the ground to facilitate reading or viewing of the same; the giving of the units (letters or characters and buoyant bodies secured to the rear faces thereof and 50 coincident in outline therewith to present in effect rearward extensions thereof) very substantial depth to give the appearance of block letters or characters, and in the instance of night illumination, creating the effect of 55 bodies shading to nothingness away from the

brilliant face of the device or, stated differently, giving the optical illusion of letters or characters projected out of remote regions to the point of the illuminated face; the permitting of a slight sway of the individual buoyant rear extension of each letter or character, while holding the latter in rigid relationship with companion letters or characters so that by reason of such fixed relationship a clear reading is assured while at the same time slight movement or sway of the buoyant extensions will create the optical impression on the reader that each character or letter is projected or suspended alone and independently of the others.

70 Other and further objects will more fully appear from the following description.

That the invention may be more fully understood reference is had to the accompanying drawings forming part of this description 75 illustrating a preferred embodiment of the invention, in which:—

Fig. 1 is a face view of a sign embodying my invention;

Fig. 2 is a top plan view of Fig. 1, parts of 80 two of certain of the buoyant containers being broken away;

Fig. 3 is an enlarged cross-section as the same would be if taken on the line 3—3, Fig. 1;

Fig. 4 is an enlarged cross-section as the same would appear if taken on the line 4—4, Fig. 2;

Fig. 5 is a face view of a sign corresponding to Fig. 1 and showing one form of supplemental buoyant means applied to the otherwise complete device of Fig. 1, part thereof broken away;

Fig. 6 is a view similar to Fig. 5 showing a modified form of the supplemental buoyant means, and

Fig. 7 is a view similar to Fig. 5 showing a further modified form of the supplemental buoyant means.

Like characters of reference denote corresponding parts throughout the figures.

In the drawings I have shown a sign which exhibits the name of an incorporated company, which is merely illustrative of one manner and form in which a display sign may be used, and it will be apparent from this disclosure that words or phrases may be spelled out so as to be visible to those that read the message or information which is intended to be conveyed by the sign. There

is no limitation as to the character of the advertising matter or information which may be displayed or the extent of such advertising matter, as the sign may be made 5 of any suitable size to fit the occasion for which it is intended to be used. Furthermore, the sign may have embodied therein any letter or letters and likewise any character or characters and even in the form of 10 symbols or designs, monograms, trademarks, trade-names, abbreviations of any such, and in fact, any character of indicia.

Since each and all of the characters or letters employed in the sign are substantial 15 replicas of each other, in so far as general structure is concerned, with the exception of their characteristics which define them as distinct and individual characters or letters of reference, it is thought that the description of one will suffice for all, without 20 repetition of detailed description.

1 designates a bag, container or receptacle of any suitable light weight material designed for being inflated with hydrogen, 25 helium or other relatively light gas, such as is usually employed in aerial devices for making them buoyant, whereby the same may be maintained in elevated position. A suitable nipple or valve 2 being provided at an accessible point whereby to permit the ingress 30 or egress of the sustaining gaseous medium into and from the receptacle. This bag, container or receptacle is not only hollow in form, as is obvious, but also embodies or 35 defines the outline of some predetermined character, letter, symbol or the like; as for example, any of the individual letters shown in Fig. 1, and more particularly shown in cross section in Fig. 4, or any other designating 40 character.

Associated with the bag, container or receptacle 1, in the composite structure, is a structural shape 3 which embodies or defines a similar designating character as that 45 of such bag, container or receptacle and is so associated therewith as to present and provide a facing therefor. This structural shape is preferably made of a light, rigid material.

50 The structural shape 3 is preferably of box-like formation and formed with a continuous outline wall or walls 4 whereby to indicate a definite designation, such as a letter, character or the like and is also provided 55 with a rear wall 5 and an open face 6 and thereby provides a recess within the shape and of like designating character therewith. The inner surfaces of the walls 4 and 5, singly or together, may or may not be burnished 60 or polished or treated in any manner to provide reflecting surfaces or they may be coated by applying thereto any suitable coloring matter or coating.

Associated with each shape 3 is a suitable 65 illuminating device 7 which preferably em-

bodies or defines the outline of the shape 3. In its preferred form, this illuminating device is located within the recess formed by the shape 3 and is protected by the wall or walls 4. I also prefer to provide a resilient support or supports 8 for the illuminating device, within the shape 3 which act to protect such illuminating device from undue shock, vibration, etc.

70 In the drawings, I have preferably shown the illuminating device of the type generally known as the "Neon" tube but it is to be understood that any other form or type of illuminating device suitable for the purpose may be used. Such illuminating device may be provided in colors as occasion or practice may require or be deemed desirable.

75 The elements 1, 3 and 7, which form a composite structure, may be so designed that they constitute the unitary element of the sign, and yet it is obvious, that such unitary elements may be arranged in series, and of whatever character suitable for the purpose, so that when assembled as a complete sign may 80 display the sign "John Doe Inc." as disclosed in Fig. 1, or in any other suitable arrangement as may be desired.

85 It will be observed, from the inspection of Figs. 2 and 3, that each unitary element (including parts 1, 3 and 7) is of very substantial depth from face to rear, and that the letter or character 3—7 constituting the face is comparatively thin or shallow while the main body portion comprising the buoyant member 1 is relatively deep. This has many substantial advantages. The latter when inflated is coincident, marginally inside and outside, with the letter or character to give body or block appearance to the same, thus enabling the basic necessity for a large gas body of 90

100 abundant capacity to be met without marring or tending to obscure the matter to be depicted. Also, attending the rearward enlargement or extension of the buoyant body of each letter or character other highly important features are developed. In the case of illumination of the face letter or character at night the effect will be that the same is shaded off from the face to the rear or conversely that the letters come out of the darkness and flare or diverge to the illuminated face thereof. Furthermore, by reason of the fact that the buoyant body of each letter or character unit is fastened to the back thereof, only, and the confining framework permitting slight sway of the buoyant body laterally in the framework, the letters or characters will to the eye appear as independently suspended while as a matter of fact the letter or character faces will be positively and rigidly held in relative position to insure perfect sight or reading thereof.

105 110 115 120 125 130 As an embracing and supporting structure for one or more of the composite elements, I preferably provide a skeleton structure com-

- prising the straps or bands 9 of some light and rigid material which preferably are secured by suitable means to the top and bottom walls of the shape or shapes 3, and secured to said straps or bands 9, in some suitable manner, are straps or bands 10 which extend rearwardly from the shape or shapes 3 and then transversely to the rear of one or more of the composite elements whereby to act as a confining and stabilizing means for the receptacle or receptacles 1, and such confining means is supplemented by the additional straps or bands 11 which overlie and underlie such receptacle or receptacles 1 and are suitably secured at their intersections with the band or bands 10, in the manner shown. As will be obvious, the skeleton frame structure just described will conform to the height, length and width of the sign when composed of one or more of the composite elements which include these designated 1, 3 and 7.

In the use of the sign, guy cables designated 12, which are connected with the straps or bands 9 included in the skeleton frame, may be employed in connection with some suitable operating means for controlling the sign and for returning the same to the ground; also, and while not shown, it is of course obvious, that some suitable conduit or wiring or other suitable electrical connections in communication with a source of electric current may be employed to convey such current to the illuminating means 3. When such illuminating means is arranged in series, it is of course understood, that they will be suitably connected for illuminating the same.

By fastening the guy cable to the strips or bands 9, as stated, it will be noted that the anchoring of the device is at a point well forwardly thereof, that is, in advance of the rearwardly projecting buoyant extensions of the letters or characters. The operating result will therefore be that when the device soars and the cables become taut, the ascension of the rear portion of the device comprising in the main the buoyant bodies, will tilt or position the face of the device at an inclination to the ground, and thereby facilitate the view or reading thereof from points distant from the immediate location in which the device is held by the cables.

Referring to Figs. 5, 6 and 7, I show modified forms of supplemental buoyant means to be used in conjunction with the sign structure heretofore described and as illustrated in Figs. 1, 2 and 3 of the drawings. In each instance, this supplemental buoyant means comprises a bag, container or receptacle of any suitable light weight material designed for being inflated with hydrogen, helium or other relatively light gas. In Fig. 5 this supplemental buoyant means is designated 13 and is shown superimposed in immediate engagement on the upper part of the sign struc-

ture 1, or 1-3 and immediately underlying the sign structure. Being immediately applied to the sign structure it may be supported, secured, connected to or associated in suitable manner therewith and such supplemental buoyant means 13 may constitute separate or individual elements.

The supplemental buoyant means as disclosed in Fig. 6 is designated 14 and in addition to overlying and underlying the sign structure 1, or 1-3 and being in immediate association therewith is also applied to the ends of the sign, so that such supplemental means appears as wholly embracing the sign.

In Fig. 7, the supplemental buoyant means is designated 15 and is shown as being only associated with the sign structure 1, or 1-3 in superimposed relation thereon.

In the preferred structure of the sign the bags, containers or receptacles 1 will be so designed and constructed that they will support each their own weight and plus the additional weight of the structural shapes 3 and associated parts, as well as the skeleton frame and connected elements well within the safety factor which may be required in a sign of this character. When necessary or when it may be deemed advisable or expedient, the supplemental buoyant means described, may be employed so that the total sum of the surface lift of the buoyant means will equal enough lifting power to support the necessary equipment employed in the sign, while at the same time have sufficient excess lifting power to guarantee the satisfactory operation of the sign.

What I claim is:

1. An aerial sign of the buoyant type, in combination, a shape formed of light rigid material, a buoyant means of substantial depth for supporting such shape forming a backing therefor and having the outline of such shape, means to inflate such buoyant means, and means to rigidly connect composite shapes in series.

2. An aerial sign of the buoyant type, in combination, a shape formed of light rigid material, a buoyant means for supporting such shape forming a backing therefor and having the outline of such shape, means to inflate such buoyant means, illuminating means supported by such shape adapted for the illumination of the outlines thereof, and means to connect multiple composite shapes in series.

3. An aerial sign of the buoyant type, in combination, a shape of box-like formation provided with a recess therewith formed of light rigid material, a buoyant means for supporting such shape forming a backing therefor and having the outline of such shape, means to inflate such buoyant means, illuminating means supported by such shape and located within the recess thereof adapted for the illumination of the outlines thereof, and

means to connect multiple composite shapes in series.

4. An aerial sign of the buoyant type, in combination, a shape formed of light rigid material of designation formation, provided with a rear light reflecting wall and an open face, a buoyant means for supporting such shape forming a backing therefor and having the outline of such shape, means to inflate such buoyant means, illuminating means supported by such shape in association with said rear light reflecting wall adapted for the illumination of the outlines thereof, and means to connect multiple shapes in series.
5. An aerial sign of the buoyant type, in combination, a shape formed of light rigid material of designation formation, comprising a continuous outline wall or walls forming a recess therewithin, said wall or walls of the recess providing light reflecting surfaces, a buoyant means for supporting such shape forming a backing therefor and having the outline of such shape, means to inflate such buoyant means, illuminating means supported by such shape and located within the recess thereof adapted for the illumination of the outline thereof, and means to connect multiple composite shapes in series.
6. An aerial sign of the buoyant type, in combination, a shape formed of light rigid material, a buoyant means of substantial depth for supporting such shape forming a backing therefor and having the outline of such shape thereby constituting a composite structure, means to inflate such buoyant means, means to rigidly connect a composite structure in series, and an embracing and supporting structure comprising a frame work associated with such composite structure whereby to act as a confining and stabilizing means for said buoyant means.
7. An aerial sign of the buoyant type, in combination, a shape formed of light rigid material, a buoyant means for supporting such shape forming a backing therefor and having the outline of such shape thereby constituting a composite structure, means to inflate such buoyant means, illuminating means supported by such shape adapted for the illumination of the outlines thereof, means to connect said composite structure in series, and an embracing and supporting structure comprising a frame work associated with such composite structure whereby to act as a confining and stabilizing means for said buoyant means.
8. An aerial sign of the buoyant type, in combination, a shape formed of light rigid material, a buoyant means for supporting such shape forming a backing therefor and having the outline of such shape, means to inflate such buoyant means, means to connect composite shapes in series and a supplemental buoyant means in immediate association with said sign.

9. An aerial sign of the buoyant type, in combination, an inflatable container, said container interiorly and exteriorly defining a character, and a structural shape in association with said container and providing a facing therefor, said shape similarly interiorly and exteriorly defining a character corresponding to that defined by the container whereby outline and interior spaces are aligned. 75

10. An aerial sign of the buoyant type, in combination, an inflatable container of substantial depth, said container defining a character, a structural shape in association with said container and providing a facing therefor, said shape defining a character corresponding to that defined by the container, an illuminating means associated with said shape and means for assembling a plurality of such associated containers and shapes with the latter in rigid association, whereby to provide a sign displaying indicia. 80

11. An aerial sign of the buoyant type, in combination, an inflatable container, said container defining a character, a structural shape in association with said container and providing a facing therefor, said shape defining a character corresponding to that defined by the container, an illuminating means associated with said shape, means for assembling a plurality of such associated containers and shapes whereby to provide a sign displaying indicia and a supplemental buoyant means in immediate association with said sign. 85 100

12. In a sign, the combination of an inflatable body defining predetermined indicia, a facing for said body having a surface area corresponding to said body when inflated and arranged to support an illuminating means of corresponding outline. 105

13. In a sign, the combination of an inflatable body defining predetermined indicia, a light weight metallic facing for said body having a surface area corresponding to said body when inflated and arranged to support an illuminating means of corresponding outline. 110

14. In a sign, the combination of an inflatable body defining predetermined indicia, a facing for said body having a surface area corresponding to said body when inflated and a light weight metallic structure for the assembly of a series of said bodies and facings whereby the facings are held in rigid relationship. 115 120

15. In a sign, the combination of an inflatable body defining predetermined indicia, a light weight metallic facing for said body having a surface area corresponding to said body when inflated, said facing arranged to support an illuminating means of corresponding outline and a light weight metallic structure for the assembly of a series of said bodies and facings. 125 130

16. In a sign, the combination of an inflatable body defining predetermined indicia, a facing for said body having a surface area corresponding to said body when inflated and 5 arranged to support an illuminating means therefor.
17. An aerial exhibition device comprising a balloon of predetermined frontal contour, a facing member thereon of the same 10 contour registering therewith and together creating a composite character of substantial depth.
18. An aerial exhibition device comprising a plurality of characters, means for securing them in predetermined relationship, and rearward balloon extensions of the same 15 shape as the characters and extending a substantial distance rearwardly therefrom.
19. An aerial exhibition device comprising a plurality of characters, means for securing them in rigid predetermined relationship, and rearward balloon extensions of the same shape as the character and extending a substantial distance rearwardly therefrom, 20 the respective balloon extensions being capable of slight swaying movement relative to their respective characters.
20. An aerial exhibition device comprising a balloon of substantial depth having a 25 predetermined frontal contour, and a relatively shallow facing member thereon of the same contour registering therewith, in combination with illuminating means for the facing member, the depth of the balloon giving the effect of the facing member shading off rearwardly of the device.
21. An aerial exhibition device comprising a rigid face character and a supporting and depth-creating member therefor comprising a balloon constituting a rearward extension of the character and contoured in keeping therewith to present the appearance 35 of a block formation.
22. An aerial exhibition device comprising a rigid face character and a supporting and depth-creating member therefor comprising a balloon constituting a rearward extension of the character and contoured in keeping therewith to present the appearance 45 of a block formation, the rigid face character being provided with illuminating means.
23. An aerial exhibition device comprising a series of balloons shaped as letters of the alphabet, facing members therefor of corresponding shape, and means engaging the 55 facing members fixedly securing them in predetermined relationship.
24. An aerial exhibition device comprising a supporting frame, characters mounted thereon, balloon extensions on the characters, and means associated with the supporting 60 frame for confining the balloon extensions to a relatively restricted zone.
25. An aerial exhibition device including a frame structure formed of longitudinally extending members and connecting end portions, characters positioned in and carried by the frame, balloon-like members extending from the characters positioned in the frame, and members connected to the frame and positioning the balloon-like members. 70
26. An aerial exhibition device including a frame structure formed of longitudinally extending members and connecting end portions, characters positioned in and carried by the frame, said characters being formed to receive an illuminating element and constituting braces for opposite portions of the frame, and balloon-like members extending from the characters. 75
27. An aerial exhibition device including a frame structure formed of longitudinally extending members and connecting end portions, characters positioned in and carried by the frame, said characters being formed to receive an illuminating element, balloon-like members extending from the characters, positioning members extending from the frame and extending around the rear faces of the balloon-like members, and positioning members connected to the first mentioned positioning members and extending over and beneath the balloon-like members. 80
28. An aerial exhibition device comprising a display facing, means for holding the same in predetermined position to prevent relative flexure or displacement of any portion of said facing with reference to the remainder thereof, buoyant means located in rear of said facing and in juxtaposition therewith, and a confining framework for said buoyant means maintaining the same in a zone substantially aligned with the facing, the limits of said zone being defined by the marginal edges of the facing. 85
29. An aerial exhibition device comprising display facing, means for holding the same in predetermined position to prevent relative flexure or displacement of any portion of said facing with reference to the remainder thereof, buoyant means located in rear of said facing and in juxtaposition therewith, and a confining framework for said buoyant means maintaining the same in a zone substantially aligned with the facing, the limits of said zone being defined by the marginal edges of the facing, in combination 90 with supplemental buoyant means cooperatively associated with said first mentioned buoyant means. 95
30. An aerial exhibition device comprising a display facing, means for holding the same in predetermined position to prevent relative flexure or displacement of any portion of said facing with reference to the remainder thereof, buoyant means located in rear of said facing and in juxtaposition therewith, and a confining framework for said buoyant means maintaining the same in a zone substantially aligned with the facing, the limits of said zone being defined by the marginal edges of the facing, in combination 100 with supplemental buoyant means cooperatively associated with said first mentioned buoyant means. 105
31. An aerial exhibition device comprising display facing, means for holding the same in predetermined position to prevent relative flexure or displacement of any portion of said facing with reference to the remainder thereof, buoyant means located in rear of said facing and in juxtaposition therewith, and a confining framework for said buoyant means maintaining the same in a zone substantially aligned with the facing, the limits of said zone being defined by the marginal edges of the facing, in combination 110 with supplemental buoyant means cooperatively associated with said first mentioned buoyant means. 115
32. An aerial exhibition device comprising display facing, means for holding the same in predetermined position to prevent relative flexure or displacement of any portion of said facing with reference to the remainder thereof, buoyant means located in rear of said facing and in juxtaposition therewith, and a confining framework for said buoyant means maintaining the same in a zone substantially aligned with the facing, the limits of said zone being defined by the marginal edges of the facing, in combination 115 with supplemental buoyant means cooperatively associated with said first mentioned buoyant means. 120

In witness whereof, I have hereunto set my hand, this 25th day of February, 1933.

WENDELL C. KEENER.
